UNITED STATES PATENT OFFICE.

ALBERT D. CARTWRIGHT AND ALFRED BAER, OF TOLEDO, OHIO.

HORSESHOE-CALKING MACHINE.

1,203,978.

Specification of Letters Patent.

Patented Nov. 7, 1916.

Application filed May 10, 1915. Serial No. 27,119.

To all whom it may concern:

Be it known that we, ALBERT D. CARTWRIGHT and ALFRED BAER, citizens of the United States, and residents of Toledo, in the county of Lucas and State of Ohio, have invented a certain new and useful Horseshoe-Calking Machine; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to horse-shoe calking machines.

The object of our invention is the provision of a simple, efficient and improved machine of the character described, which is operable to perform several distinct operations on a horse-shoe in the course of manufacture, namely, turning over the heel calks, upsetting and shaping the same to adapt them for summer or winter use, welding the toe calk on the shoe and then shaping it, and also forming a shoe with the block form of heel calks, thereby materially simplifying the calking of horse-shoes and enhancing the practicability and commercial value of machines of this class.

Further objects and advantages of the invention will be apparent from the following detailed description thereof.

The invention is fully described in the following specification, and while, in its broader aspect, it is capable of embodiment in numerous forms, a preferred embodiment thereof is illustrated in the accompanying drawings, in which,—

Figure 1 is a side elevation of a machine embodying the invention and illustrating the heel calk turning operation. Fig. 2 is a front elevation of the machine, with parts broken away, and with a horse-shoe in heel calk upsetting position. Fig. 3 is a central vertical section of the upper portion of the machine with the parts in heel calk upsetting position. Figs. 4 and 5 are enlarged sectional details of a portion of the machine illustrating the heel calk turning over means

which is used when forming a block type of heel calk, the calk shaping dies being removed. Fig. 6 is a similar view with toe calk shaping dies in position and acting on a horse-shoe, and with the welding and block heel calk forming die removed. Fig. 7 is a view similar to Fig. 6 with the block heel calk shaping die in position and acting on a horse-shoe. Fig. 8 is a similar view with toe calk crimping dies in position and acting on a horse-shoe, and with the welding die in position and acting on the toe calk of a horse-shoe to weld it to the shoe body, and Fig. 9 is a bottom view of a horse-shoe having block heel calks and a crimped toe calk.

Referring to the drawings, 1 designates a machine frame or standard, which is provided at its front side with a forwardly, 70 upwardly and rearwardly extending yoke or arm 2, and at the rear of said arm the frame is provided with the upwardly extending transversely spaced arms 3 and 4 which coöperate to form a fork as shown. 75

The arm or yoke 2 is provided in a vertical plane in its free end with an opening through which a stem 5 projects, said stem carrying at its lower end an anvil-die 6 and at its upper a head 7. A coiled compression spring 8 is interposed between the arm 2 and head 7 to yieldingly hold the die 6 seated against the under or inner side of the arm. The die 6 may be turned relative to the arm 2 to bring different of its 85 lower edges into operative position, as hereinafter more fully described. The die 6 when seated against the arm 2 is prevented from turning relative thereto by coaction at one of its edges with a shoulder 9 on the 90 arm. In order to turn the die it is necessary to force the stem 5 and die inward a sufficient distance to escape or free the shoulder 9.

Pivoted within the arm 2, as at 10, is a substantially L-shaped pressure block 11, which extends rearward from said pivot and then upward through the registering top portion of the frame 1 and in position, when raised, to bear upward at its free end against the 100 anvil-die 6, or against an interposed horse-shoe or other work piece a to clamp it firmly

to the die 6, as shown in Fig. 1. A foot-treadle 12 is pivoted, as at 13, in the base portion of the frame 1 and has connection at the rear of its pivot through a connecting rod 14 with the pressure block 11 at the angle portion thereof, whereby a lowering of the outer end of the treadle from the dotted line position to the full line position in Fig. 1 effects a raising of the pressure block 11 into operative work clamping relation to the die 6.

A shaft 15 extends between and is journaled at its ends in the upper ends of the fork arms 3, 4, and is provided at one end 15 with a crank-handle 16 to facilitate a hand turning of the shaft. Fixedly carried by the shaft 15 between the fork arms is a heavy fly-wheel 17 that is provided, in the present instance, on the side thereof adjacent to the 20 fork arm 3, with an eccentric or cam shoulder 18, which extends entirely around the axis, and is for the purpose hereinafter described.

A frame part or head 19 is pivoted, as at 25 20, within a vertically disposed recess or groove 21 in the outer side of the fork arm 3 and is secured at its lower end in adjusted relation to the fork arm by a screw 22, which passes through an aperture in the lower end 30 of the frame part or head and threads into the base portion of the frame fork, as shown in Fig. 3. The frame part or head 19 has two arms or ledges 23 and 24 projecting outward in spaced superimposed relation therefrom, and, in the present instance, at opposite sides of the pivot 20. The arm or ledge 23 has a seat on the top of its outer end portion for a heel calk upsetting die 25 and has an opening extending vertically there- 35 through from said seat for the die stem 26 to project through. The lower end of the die stem 26 is preferably provided with a removable head 27, which permits the die and stem to have limited vertical movements 40 relative to the arm 23 and facilitates a turning thereof. The inner edge of the upsetting die 25 coacts with a shoulder on the arm 23 to prevent a turning of the die when seated in operative position on the arm. The 45 die 25 has calk upsetting recesses 28 of different depths in different top edges thereof, any one of which may be placed in operative position by a turning of the die.

An operating lever 29 is fulcrumed to the 55 upper end of the frame part or head 19 above the arm or ledge 24 thereof, as at 30, in transverse relation to the plane of rotation of the wheel 17 and has its inner end of sufficient length to project over the cam 60 shoulder 18 of the wheel and carrying a roller 31 for riding on said shoulder at the top side thereof. The eccentric or cam form of the shoulder 18 causes the lever 29 to have predetermined oscillating movements when

the wheel 17 is rotated. Pivotally depend- 65 ing from the lever 29, at a point without its fulcrum 30, is an upsetting plunger 32, which is provided at its lower end over the inner recessed edge of the up-setting die 25 with a recess 33, which, when the plunger is 70 lowered, is intended to fit over the inner heel edge of a horse-shoe *a* and force the calk *b* of the horse-shoe into the registering recess 28 of the die 25 to effect a desired up- 75 setting of a calk. A toggle link 34 is in- 80 terposed between the front or outer side of the frame part or head 19 and the free end portion of the upsetting plunger 32, being pivotally connected to each as shown. When 85 the plunger is in raised position the link 34 stands at an upward incline from the frame part or head 19, as shown in Fig. 2, and when the plunger is lowered the link causes a limited outward swinging of the free end of the plunger to force it outward into up- 90 setting relation with the outer side of a heel calk, which is being acted on. It is thus evident that the plunger 32 has a compound downward and outward pressure on a heel calk to coöperate with the die 25 to effect a desired upsetting thereof.

The upper frame or ledge 24 of the frame head 19 is of forked form and has the inner sides of its fork arms provided with registering longitudinally extending grooves or 95 recesses 35. A die block 36 is removably mounted within the forked end of the arm 24, being provided for such purpose with ribs, which slidingly engage within the grooves 35 of the arm. The inward movement of the die block 36 within the forked end of the arm 24 is limited by the length of the grooves 35 and also by shoulders 37 within the forked portion of the arm. The die block 36 is disposed below the extended jaw 100 end 29^a of the lever 29 and is intended to co- 105 operate with said lever both to partially form a block type of heel calk *c*, as shown in Figs. 4 and 5, and to force a toe calk *d* of a 110 horse-shoe into welding relation with the shoe, as shown in Fig. 8. To facilitate the use of the die 36 for calk turning purposes the die is provided at one end thereof with a spur 36', which, when the die is in operative 115 position for turning a block heel calk *c*, ex- 120 tends outward and upward from the outer end of the die block and beyond the end of the jaw 29^a, as shown in Figs. 4 and 5. The surface of the die 36, of which the spur 36' forms a continuation, is preferably pro- 125 vided with flattened steps 38 for use in conjunction with the jaw 29^a when a broad or summer type of toe calk is to be welded to a jaw. The opposite side of the die block 36 is provided with different V-notches or recesses 39 to adapt it, when reversed from the positions shown in Figs. 4 and 5 and dis- 130 posed in the position shown in Fig. 8, to be

used in connection with the welding of sharpened or winter toe calks to a shoe, as illustrated in Fig. 8. When welding a toe cork to a shoe the cork is placed in engagement 5 with the proper surface of the die block 36 and the shoe is disposed over the cork in position for the jaw 29^a of the lever and the die block 36 to force the cork and shoe into welding relation.

10 The frame part or head 19 has its upper end extended a short distance above the lever pivot 29 and provided in its top with a recess 40 for removably receiving a cork shaping die 41 of desired form. The lever 15 29 at the rear of the upper extended end portion of the frame head 19 is provided with a shoulder in opposition to the recessed portion of the head and this shoulder is provided with a recess or socket 42 for removably receiving the shank of a cork shaping die 43. If it is desired to shape a heel cork of block form, as shown in Fig. 7, the proper dies 41 and 43 for such purpose are secured in position and the wheel 17 turned to effect 20 an oscillating of the lever 29, which forces the die 43 toward the die 41 and effects the desired shaping of the cork. The dies 41 and 43 may be changed to suit the work to be performed, as different dies are used in connection with the shaping of different forms 25 of heel calks and different forms of nose calks, as is apparent by reference to Figs. 3, 6, 7 and 8. The upper end of the frame head 19 is provided with a horizontally-disposed extension or arm 44 for supporting the outer end portion of a shoe when a cork 30 thereof is being shaped by a set of dies 41, 43.

In order to adapt the machine to be used 40 for the severing or cutting off of metal articles, the lever 29 is provided on one side of its outer end portion with a shearing die or plate 45 (Figs. 1 and 2), which, upon a downward rocking of the outer end of the lever, has shearing coaction with a stationary 45 shearing die or plate 46 on a side of the frame head arm 24.

The fly-wheel 17 is provided on its periphery with a radially projecting boss 47, which is provided on the forward side thereof, relative to the direction of rotation of the wheel, with an inclined wiper plate or surface 48, which is disposed to have wiping coaction with the heel end of a shoe when clamped by the anvil-die 6 and pressure-block 11 and extended a short distance therefrom toward the wheel, as shown by dotted lines in Fig. 1. The coaction of the wiper surface of the boss 47 with the heel end of a horse-shoe, when clamped as shown in Fig. 1, causes an upward bending of the heel end portion at its outer end with a roller 49, which projects slightly beyond the outer end of the inclined wiper surface 48 and coacts

with the registering heel end of the horse-shoe to complete the upward bending thereof, as is apparent by reference to Fig. 1.

In the use of our improved machine the operation of the same in connection with the forming of calks on horse-shoes is as follows: In forming the heel cork the heel end of a horse-shoe is clamped between the anvil-die 6 and pressure block 11 with the end thereof projecting a desired distance beyond the die and pressure block in the direction of the wheel 17 and in the path of revolution of the boss 47. The wheel 17 is then given a single turn in the direction of the arrow in Fig. 1, thereby causing the wiper surface 48 and roller 49 of the wheel 80 boss to have wiping coaction with the extended end of the horse-shoe and to bend it in upright position or at right angles to the body of the horse-shoe, as indicated in Fig. 1. This having been done the cork is placed 85 over the upsetting die 25 in the manner shown in Fig. 2, and the wheel 17 then given another turn to rock the lever 29 and force the upsetting plunger 32 into engagement with the heel end of the horse-shoe to co-operate with the die 25 to impart the desired upsetting action to the cork. The heel cork is then placed between the desired set of shaping dies 41 and 43 and the wheel 17 turned to rock the lever 29 and cause a relative movement of the shaping dies to give the final shape to the cork to suit the same for winter or summer use, as desired. These successive operations may be performed in such rapid order that a single heating will 100 suffice for all operations. It will be understood that the heel calks *b* may be made of any desired depth by extending the end of the shoe a greater or less distance beyond the edges of the die 6 and pressure block 11. 105 When it is desired to make the cork of block form the initially bent-up portion of the shoe is made of sufficient length for such purpose and the heel end of the shoe is then placed between the clamping jaw 29^a of the 110 lever and the turning spur 36^a of the die block 36, said die block being first positioned with the spur 37 thereof projecting upward from its outer end, as shown in Figs. 4 and 5. When the lever is operated by a turning of 115 the wheel 17 the bent-up cork portion of the shoe is doubled over on the heel end of the shoe, as shown in Fig. 5. This cork is then given the desired shape by compression between the desired set of dies 41, 43, as shown 120 in Fig. 7. In affixing a toe cork *d* to a shoe the stem of the cork, after being heated, is inverted or partially inserted into the aperture provided therefor in the shoe, and the toe portion of the shoe and cork are then 125 placed between the die-block 36 and lever jaw 29^a, with the cork resting on the die-block, and the lever is operated by a turn-

ing of the wheel 17 to effect a forcing together of the calk and shoe and a consequent close welding of the same. If a summer type of calk is used the die-block 36 is preferably positioned with the flat surface 38 thereof disposed at its top side, and if the calk is of the winter or sharp type the V-notched surface of the die block is placed uppermost, as will be readily understood from the drawings. The welding operation having been effected the toe calk is placed between the desired set of shaping dies 41, 43 and the lever operated to impart the final shape to the calk. Should wear occur between the parts of the lever and wheel, which coöperate to impart rocking movements to the lever when the wheel is turned, such wear may be compensated for by an adjustment of the frame part or head 19 relative to the wheel carrying fork of the frame. This adjustment may be accomplished by inserting a block or shim piece of desired thickness between the lower end of the head 19 and the base of the fork arm groove 21, the screw 22 being loosened and then tightened again for such purpose.

It will be understood that we have provided a simple and efficient machine which is adapted to perform all the necessary operations in forming or affixing calks to a horse-shoe and then imparting the desired shape thereto. It is also apparent that the lever 29 has a manifold purpose in that it is utilized in conjunction with the plunger 32 and die 25 to upset a heel calk; in conjunction with the die block 36 to double over a heel calk in block form, and to weld a toe calk of either summer or winter form to the shoe; and in conjunction with the upper end of the frame head 19 and the dies 41 and 43 to impart the final shaping action to either the heel or toe calks. In addition to the above the lever 29 is also operable to impart shearing movements to the shearing die 45 with respect to the shearing die 46.

We wish it understood that our invention is not limited to any specific construction, arrangement or form of the parts as it is capable of numerous modifications without departing from the spirit of the claims.

Having thus described our invention, what we claim as new, and desire to secure by Letters Patent, is,—

1. In a machine of the class described, a frame, a lever carried for rocking movements by said frame, means mounted for complete successive rotary movements and having a cam part for coacting with and imparting oscillatory movements to said lever, and a die block carried by said frame and operable in conjunction with said lever when rocked to act on a horse shoe calk to shape the same.

2. In a machine of the class described, a

frame, a head adjustably carried by said frame, a lever fulcrumed in said head, means rotatably carried by the frame and operable to impart rocking movements to said lever, and a die carried by said head and operable in conjunction with said lever when rocked to act on a horse shoe calk to impart shaping movements thereto, said head being adjustable to compensate for wear between said lever and rotatable means.

3. In a machine of the class described, a frame, a lever carried for rocking movements by said frame, a rotatable wheel having a cam part for operating said lever, and a die block carried by said frame and operable in conjunction with said lever when rocked to shape a horse shoe calk.

4. In a machine of the class described, a frame, a lever carried for rocking movements by said frame, rotatable means for operating said lever, and a die block removably carried by said frame and usable in different positions with respect to said lever to coöperate therewith to perform different operations on horse-shoe calks.

5. In a machine of the class described, a frame part having a forked arm with the inner sides of the fork arms grooved inward from the outer ends thereof, a die block having portions for sliding engagement with said grooves whereby the block can be removably carried by the arm, a lever carried by said frame part and having a jaw which is operable upon a rocking of the lever to coact with said die block in the performance of predetermined work, and rotatable means for imparting rocking movements to said lever.

6. In a machine of the class described, a frame, a head adjustably carried by said frame, calk shaping means carried by said head, and means carried by said frame and operable to actuate said shaping means, said shaping and operating means being relatively adjustable by an adjustment of said frame and head.

7. In a machine of the class described, a frame, a revoluble cam member mounted in said frame, a head pivoted to said frame for adjustment with respect thereto, and calk shaping means carried by said head and operated by a revolving of said cam member.

8. In a machine of the class described, a frame having a die carrying part, a fly-wheel mounted in said frame and having a cam part, a die carried by said frame part, a lever fulcrumed to said frame and operable by the cam part of said wheel when rotated to coöperate with said die to shape a horse-shoe calk.

9. In a machine of the class described, a forked frame having a die holding part projecting transversely from one arm thereof, a wheel rotatably mounted in the fork

of said frame and having a cam part, a die carried by said frame part, a lever fulcrumed to said frame at one side of the wheel transversely thereof and having one 5 end projecting over the cam part of said wheel, an anti-friction roller carried by said lever for riding on said cam part, said lever

being operable by a rotation of the wheel to coöperate with said die to shape a horse-shoe calk.

In testimony whereof, we have hereunto signed our names to this specification.

ALBERT D. CARTWRIGHT.
ALFRED BAER.
